W. TUPPER.

CENTRIFUGAL BRAKE FOR FIRE ESCAPES.

APPLICATION FILED APR. 19, 1915.

1,174,300.

Patented Mar. 7, 1916.

UNITED STATES PATENT OFFICE.

WILLIAM TUPPER, OF BISHOP'S CROSSING, QUEBEC, CANADA.

CENTRIFUGAL BRAKE FOR FIRE-ESCAPES.

1,174,300.

Specification of Letters Patent.

Patented Mar. 7, 1916.

Application filed April 19, 1915. Serial No. 22,351.

To all whom it may concern:

Be it known that I, WILLIAM TUPPER, a subject of the King of Great Britain, and resident of Bishop's Crossing, in the Province of Quebec, Dominion of Canada, have invented certain new and useful Improvements in Centrifugal Brakes for Fire-Escapes, of which the following is the specification.

- 10 This invention relates to improvements in fire escapes and the objects of the invention are to render the device compact in construction thereby occupying a minimum of space and capable of being packed in a hand grip 15 so adapting it for traveler's use, to facilitate in hanging the fire escape to a window sill or like support, to govern the speed of descent and generally to adapt the several parts to better perform the functions required of them, and it consists essentially of 20 the improved construction particularly described and set forth in the following specification and accompanying drawings forming part of the same.
- 25 In the drawings, Figure 1 is a perspective view of the improved fire escape as seen when hung from a window frame. Fig. 2 is a sectional elevation of the improved fire escape. Fig. 3 is a plan view of the speed 30 governing mechanism. Fig. 4 is a plan view of the internal pinion gearing. Fig. 5 is a perspective view of the clutch jaws formed integral with one of the pinion wheels.

Like characters of reference refer to like 35 parts in the several drawings.

Referring to the drawings, A represents a window frame and B the improved fire escape hung from the sill thereof. The escape B comprises a casing preferably made in three sections 10, 11 and 12 adapted to be secured in assembled position by the set screw 13 or the like and having orifices 14, 15 and 16 through the centers thereof, in the first and last of which orifices the spindle 17 is rotatably mounted. This spindle is adapted to be manually operated and to this end is provided with a hinged lever 18 rigidly mounted on one end thereof.

Rigidly mounted on the spindle 17 is a 50 drum 19 having its inner face recessed at 20 and provided on diametrically opposite sides of the spindle with orifices 21 in which the cylindrical spring controlled plugs 22 are slidably mounted, the said drum being 55 connected on its outer periphery with the

inner end of the steel tape 23 coiled therearound.

Cooperating with the cylindrical plugs 22 are concentrically located clutch jaws 24 formed integral with the face of the pinion 30 wheel 26 rotatably mounted on the cylinder 17, and adapted to mesh with the pinion wheel 26 rotatably mounted on the cylindrical projection 27 formed integral with the central section 11 of the casing. 65

Meshing with the pinion wheel 26 is a second pinion wheel 28 rotatably mounted on the spindle 17 and formed with an integral squared boss 29 on which the governing mechanism C is adapted to be carried. 70 This governing mechanism comprises a lever 30 of substantially Z-shape provided with a squared orifice 31 through the center thereof adapted to engage with the squared boss 29 of the pinion wheel 28, the ends of 75 the offset arms of the said lever terminating in curved jaws 32, the object of which will be made clear hereafter.

Pivotedly mounted on the lever 30 intermediate of their lengths are a pair of levers 80 33, the shorter arms of which are formed with curved jaws 34, the longer arms being offset at substantially right angles and terminating in suitable balance weights 35. The outward motion or action of the balance 85 weights 35 is controlled by the springs 36 connected to the levers 33 and 30 respectively.

Cooperating with the jaws 32 and 34 are curved strips 37 of suitable resilient material, having their ends formed with cylindrical projections 38 and 39 designed to engage and be embraced by the curved jaws 32 and 34, the outer periphery of the said members being suitably covered with leather 90 or like material. The outer end of the tape 23 is provided with an adjustable body strap 45. The sections 10 and 12 of the casing are provided with integral brackets 40 and 41 to which one end of the suspending bridle 42 100 is attached, the other end being attached to a suitable hook 43 adapted to take around the window sill or like object to which the fire escape is to be hung. On that side of the casing diametrically opposite the bridle 105 the sections 11 and 12 are provided with a rectangular orifice 44 through which the tape 23 is designed to pass.

When in use the escape A is overhung from a window, the hook 43 being secured to 110

a suitable support, the body strap being adjusted around the wearer and the descent made under gravity. Due to the uncoiling of the tape 23 the drum 19 is rotated thereby transmitting motion through the medium of the cylindrical plugs 22 engaging the clutch jaws 24 to the pinion wheel 25 which meshes with the pinion wheel 26 and in turn rotates the intermeshing pinion wheel 28 so 10 operating the speed governing mechanism C. Should the speed of the descent exceed a predetermined limit the levers 33 are, due to the centrifugal force of the balance weights 35, actuated, causing the curved 15 strips 37 to be expanded thereby engaging the leathered outer face with the inner periphery of the section 10, so retarding the descent. After the descent has been made the tape 23 is recoiled by means of the manually operated lever 18 on the drum 19 prior to a second descent being made. It should be clearly noted that during this operation the pinion wheel 25 is stationary since the clutch jaws 24 are formed with cam surfaces 20 to enable the spring controlled plugs 22 to be freed therefrom so that the governing mechanism is only called into play during descent thereby permitting of the tape 23 being recoiled on the drum 19 as rapidly as 25 desired.

Although in the embodiment illustrated I have shown one tape 23 it will be understood that a plurality of such tapes may be mounted on the drum 19 if such be found desirable.

Copies of this patent may be obtained for five cents each, by addressing the "Commissioner of Patents, Washington, D. C."

As many changes could be made in the 35 above construction and many apparently widely different embodiments of my invention, within the scope of the claim, constructed without departing from the spirit or scope thereof, it is intended that all matter contained in the accompanying specification and drawings shall be interpreted as 40 illustrative and not in a limiting sense.

What I claim as my invention is:

In a fire escape, a speed controlling mechanism comprising a substantially Z-shaped lever operatively mounted intermediate of its length and having curved jaws on its opposite ends, a pair of levers pivotally mounted intermediate of their length to the Z-shaped lever and having curved jaws on the ends of the shorter arms, the ends of the longer arms being offset at substantially right angles and terminating in balance weights, resilient means for returning the 55 last said levers to a normal position, and strips of resilient material having cylindrical ends adapted to engage and be embraced by the curved jaws of the said Z-shaped lever and the last said pair of levers, substantially as described.

In witness whereof I have hereunto set my hand in the presence of two witnesses.

WILLIAM TUPPER.
